O. May Edwards
ATTORNEY

UNITED STATES PATENT OFFICE

JOSEPH F. FLYNN, OF BROOKLYN, NEW YORK

FOOTPAD

Application filed July 30, 1931. Serial No. 554,030.

The object of my invention is to provide a foot pad of this sort which is made of resilient material, such as sponge rubber, and shaped so as to be placed inside a shoe of a wearer, and, when in use, properly support the metatarsal bones and other parts of his foot, so that the wearer will be caused to walk normally and feel comfortable at all times and have his foot properly supported. This and other objects are accomplished by my invention, one embodiment of which is hereinafter more particularly set forth.

For a more detailed description of my invention, reference is to be had to the accompanying drawing, forming a part hereof, in which

Figure 1 is a plan view of a left foot pad embodying my invention;

Figure 2 is a similar view of a right pad;

Figures 3 and 4 are sectional views taken on the lines 3—3 and 4—4 of Figure 1, looking in the direction of the arrows.

Throughout the various views of the drawing, similar reference characters designate similar parts.

In the preferred embodiment of my invention, each foot pad 1 is composed of sponge rubber, or similar material, and shaped with a portion 2 of maximum thickness, which may run from 6/16 of an inch at the edge 3 to 4/16 at the line 4, or be given any other suitable dimension. From the line 4, there is a more abrupt slope to the line 5 where the thickness may be substantially 3/16 of an inch, and from here to the outer edge 6, the slope is gradual with the edge 6 at substantially 2/16 of an inch. These thicknesses may be varied as desired.

The under surface 7 is flat, or substantially so. It will be noted that the exterior and interior lines are so placed that the heel is properly supported at 8, the transverse arch near the line 3—3 of Figure 1, and the metatarsal arch at or about 9, and that the front portion of the part 2 projects forward so as to get under the metatarsal joints and properly support the same.

Experience has shown that when pads made as above described have been placed in the shoes of a wearer who has weak feet and a

tendency to pronation or outward splaying, or any other trouble, the various parts of each foot were properly supported so that the wearer walked normally and felt comfortable in using these pads.

It is important to use a very resilient and soft material such as sponge rubber and if desired, such may be covered by a suitable coating of ordinary rubber so as to facilitate cleaning.

It is often desirable, but not essential, to incline the extreme inner edge of the bottom 7 as indicated at 10, so as to enable the pads to more properly fit the shoe of the wearer.

While I have shown and described one embodiment of my invention, it is obvious that it is not restricted thereto but that it is broad enough to cover all structures that come within the scope of the annexed claim.

Having thus described my invention, what I claim is:

An arch supporting pad for insertion in a shoe, comprising a resilient member of the general outline of the shoe sole at the heel and shank portion, having a raised supporting portion adapted to underlie only the heel, the inner longitudinal arch, and the metatarsal arch of a foot, and a boundary portion sloping from the raised supporting portion to a marginal portion at a lower level, the edge of said marginal portion serving accurately to position the pad within the shoe.

In testimony whereof, I have hereunto set my hand this 27th day of July, 1931.

JOSEPH F. FLYNN.
